CLAIM

The ornamental design for a corner mounted speaker, as shown and described.

DESCRIPTION

FIG. 1 is a front elevational view of a corner-mounted speaker showing my new design;

FIG. 2 is a right side elevational view thereof, the left side being a mirror image;

FIG. 3 is a rear elevational view thereof;

FIG. 4 is a top plan view thereof, rotated 90° degrees from FIG. 1;

FIG. 5 is a bottom plan view thereof, rotated 90° degrees from FIG. 1; and

FIG. 6 is an elevational view of one front panel thereof, shown for clarity of illustration.
